UNITED STATES PATENT OFFICE.

JAMES M. COSGROVE, OF MALDEN, MASSACHUSETTS.

STREET AND ROAD CONSTRUCTION.

1,078,773.

Specification of Letters Patent.

Patented Nov. 18, 1913.

Application filed June 16, 1913. Serial No. 773,816.

To all whom it may concern:

Be it known that I, JAMES M. COSGROVE, a citizen of the United States, residing in Malden, county of Middlesex, and State of Massachusetts, have invented an Improvement in Street and Road Construction, of which the following description, in connection with the accompanying drawings, is a specification, like characters on the drawings representing like parts.

This invention relates to street and road construction, and more particularly to streets or roads of that character in which the wearing surface is composed of blocks of granite, wood or other material.

Roads or streets provided with a surface or wearing layer of the character described are not entirely satisfactory, owing to the fact that the individual blocks are capable of being moved by heat and cold, so that in a short time they are disturbed and moved into different positions and thereby form a very irregular or rough surface, which is highly objectionable and has to be relaid at frequent intervals.

The present invention has for its object to provide a surface or wearing layer of individual blocks or rigid members, which are locked against movement, as will be described, and which can be laid in a minimum time and at a minimum expense. To this end, the blocks are individually inclosed in forms which constitute part of the permanent wearing surface, and which are more or less adhesive and yielding for a purpose, as will be described.

The particular features of the invention will be pointed out in the claims at the end of this specification.

Figure 1 represents in cross section a street or road provided with a wearing layer or surface embodying this invention. Fig. 2, a plan of a portion of the road shown in Fig. 1, and Fig. 3, a detail in plan of one of the blocks and its form.

The street or road shown in the drawings as illustrating this invention is provided with a wearing surface or layer, which is composed of a plurality of rigid members or blocks *a*, which may be granite, wood, slag or other suitable material, and which are inclosed except at their upper surface in a form composed of side pieces or members *b* and a bottom piece or member *c*, of adhesive and yielding material, preferably sand or dust and asphalt in suitable proportions, for

instance, 15 to 25% asphalt and 85 to 75% sand or dust, which mixture forms a body, which is capable of being handled and yet is yielding and more or less adhesive under the influence of heat.

The side pieces or members *b* may be made separate from one another and from the bottom member or piece *c*, so that they may be applied to each block *a* as the latter is laid.

The blocks *a* are usually rectangular in form and have substantially smooth faces, and the members or pieces *b*, *c*, are made rectangular in shape so that they can be fitted to the blocks *a* and make close contact therewith.

The bottom pieces *c* may be made of substantially the same size as the bottom surface of each block, or, as is preferred, the bottom strip *c* may be made long enough to extend across the road or street as represented in

Fig. 1, and form the bottom strip for a row of blocks *a*. The side pieces *b* may and preferably will be made of sufficient height to project above the upper or top surface of the blocks *a*, as represented at the left in

Fig. 1, so as to form locking projections 10, which are designed to be pressed down upon and overlap onto the top surface of the blocks *a* and thereby securely lock the latter in the form against tipping movement therein, as represented at the right in Fig. 1, and thus avoid the granite or other block *a* from being tilted above the level of adjacent blocks.

The locking projections 10 may be rolled or pressed down with a heated tool, which will soften the asphalt sufficiently to enable the projections to be spread over the edges of the block without separating from the portion of the members *b* between the blocks,

and when the blocks *a* have been thus locked, a smooth or substantially smooth upper surface is imparted to the wearing layer of the street or road, as represented at the right in Fig. 2. By ironing down the projecting

upper ends of the side members or strips *b* of the form, in the presence of heat, the blocks *a* are not only locked in place, but the side members or strips are united at their upper edges so as to form a container

100 or form having sides which may be separated at their edges between the blocks *a*, but are united at their upper ends.

The wearing surface or layer referred to, may be laid upon any suitable foundation, 110 and, in the present instance, the foundation is represented as composed of a plurality

of layers, comprising a subgrade 20, a concrete layer 21, and a sand layer 22, but it is not desired to limit the invention to the particular foundation herein shown. It is preferred to make the strips or members *b* of adhesive material, such as asphalt, and a body of finely divided silicious material, such as sand, and in such proportions that the strips may have sufficient rigidity to enable them to be easily handled and transported, yet possessing sufficient plastic or adhesive material, such as the asphalt, to enable them to be rolled down without separation of the overlapping or locking edges from the portion of the strips between the blocks, and while I may prefer to employ the ingredients of the yielding members in about the proportions specified, it is not desired to limit the invention either to the particular proportions or to the particular ingredients specified.

From the above description, it will be seen that the blocks *a* are locked against tilting or being thrown out of their true or proper position under the influence of heat and cold, and further that the forms containing the blocks are capable of yielding more or less and are united at their upper edges.

I have herein represented the blocks *a* of substantially the size of paving blocks now commonly used in the streets of cities, but it will be understood that the blocks may be made of any desired size and of any desired material suitable for use in roads and streets. Furthermore, the overlapping edges form closures for the spaces between the blocks and renders the street or road sanitary and dustless.

Claims.

- 40 1. In a construction of the character described, a wearing surface composed of a plurality of blocks and strips composed of silicious material and asphalt interposed between said blocks and having their upper ends overlapping the same, substantially as described.
- 45 2. In a construction of the character described, a wearing surface composed of a plurality of blocks arranged in rows, a layer of silicious and yielding material upon

which the blocks in a row are laid, and members of silicious and adhesive material interposed between adjacent blocks and having their upper ends overlapping the upper surfaces of said blocks.

55

3. In a construction of the character described, a wearing surface composed of blocks, and yielding forms in which said blocks are located, said forms overlapping the said blocks and being united at their upper edges which overlap the blocks, substantially as described.

4. In a construction of the character described, a wearing surface composed of blocks, and forms in which said blocks are located, said forms being composed of side members of yielding and adhesive material united at their upper edges and separated at the lower portions of their side edges, substantially as described.

65

5. In a construction of the character described, a wearing surface composed of rigid members, and preformed yielding and adhesive members interposed between said rigid members and having their upper ends overlapping said rigid members to lock the latter in fixed position.

70

6. In a construction of the character described, a wearing surface composed of rigid members, and preformed yielding and adhesive members interposed between said rigid members and having their upper ends united together, substantially as described.

75

7. In a construction of the character described, a wearing surface composed of rigid members, and preformed yielding and adhesive members interposed between said rigid members a single yielding member being common to two adjacent rigid members and separated at the lower portion of its side edges from an adjacent yielding member but united thereto at the upper portion of its side edges.

80

In testimony whereof, I have signed my name to this specification in the presence of two subscribing witnesses.

JAMES M. COSGROVE.
